CLAIM

The ornamental design for a door for an indoor wall with built-in home appliances, as shown and described.

DESCRIPTION

FIG. 1 is a front perspective view of the door for an indoor wall with built-in home appliances showing our new design; FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a rear perspective view thereof; and,

FIG. 8 is a reference view showing the state of use that the claimed design has attached to the indoor wall with built-in home appliances.

The portions of FIG. 8 drawn in broken lines show environmental structure only and form no part of the claimed design.
